UNITED STATES PATENT OFFICE

2,109,488

FIRE FIGHTING TOOL

John H. Wegner, Yosemite, Calif.

Application June 7, 1935, Serial No. 25,440

2 Claims. (Cl. 97—66)

(Granted under the act of March 3, 1883, as
amended April 30, 1928; 370 O. G. 757)

The invention described herein may be manufactured and used by or for the Government of the United States for governmental purposes without the payment to me of any royalty thereon.

This invention relates to a composite tool designed more particularly as an instrument of various uses in fighting hostile fires.

In fighting forest fires, the object of the fire fighter is to denude an area, in front of the advancing fire, of combustible or inflammable material and to do so, over a given length of terrene, the fighter may require a various number of implements such as a rake; a scythe, cutting edge, or blade; a grubbing hoe, axe, trencher, or hoe; and a spade or shovel.

Implements of this character are desirable for clearing a path or area of such inflammable materials as leaves, grass, vines, brush, trees, and the like. It is also expedient and necessary at times to have at hand and employ a hoe or trencher to make furrows, dead lines, or trenches in the earth.

The territories most subject to fires are usually rough, dense and brushy, steep and mountainous. Through such territories it has been found to be almost impossible for a fire fighter to carry all of the implements that are essential and required. Such a number of necessary tools has also been found to be an incumbrance which will hamper and hinder the fighter's progress and work which must necessarily be at a rapid pace.

An object of my invention is to provide a single instrument which will accomplish the purposes and functions of such various implements as mentioned above.

Other objects of my invention will be set forth in the following description, it being understood that the above general statement of the objects of my invention is intended to generally explain the same without limiting it in any manner.

In the illustrated application of the invention,

Figure 1 is a plan view of an implement, except for the handle, having the characteristics of an embodiment of the invention and by which the invention may be practiced.

Figures 2, 3 and 4 are illustrative of cross sections A—A, B—B, and C—C of Figure 1.

Figure 5 illustrates a cross sectional view, similar to Figure 4, with a cross sectional view of a ferrule and handle and a means of attaching the same.

Figure 6 is an illustrative perspective view of my invention.

Several embodiments of my invention are

known to me but according to that by means of which I have illustrated my invention herein, I provide an elongated member 10 having a centrally disposed longitudinal raised or ridged reinforcing portion 11 which is shown extending substantially from the end 12 to the end 13 of the elongated member. This reinforcing ridge 11 preferably raises gradually, from the more or less flat surface of the elongated member to a place nearer one end of the member 10 than the other where this reinforcing ridge portion 11 terminates into an upright collar or shoulder 14 about an eyelet 15 through the member 10 into which a detachable ferrule 16 may be fitted and attached. One edge of said member 10 is serrated or terminates into a plurality of teeth or tines 17 to serve as a rake, or the like, while the opposite edge 18 of blade 18a terminates into a sharpened edge to serve as a scythe, blade, or the like. The ends 12 and 13 of said elongated member also terminate into sharpened edges, the blade 13a serves as a hoe, trencher, grubbing hoe, or the like, while the opposite or longer end 12 of the member may serve as a spade, shovel, or the like.

I have found it beneficial and advantageous, though not necessary, to have the teeth 17 of the implement slightly dished, as shown particularly in Figures 1 and 6. The edges of these teeth 17 may also be sharpened for cutting purposes.

The instrument as has already been described may be stamped, pressed, swaged, or molded from a single piece of metal, or metal alloy.

The handle shown in Figures 5 and 6 is comprised of a detachable ferrule 16 and is preferably hollow to afford maximum strength and a minimum weight. A metallic ferrule is preferred, for the particular described use of the implement, in order to prevent its catching on fire and burning; to afford sufficient strength to withstand the rough usage to which the implement must be put; to facilitate the manufacture of a ferrule and handle having a desired or proper contour, angle, or shape, i. e., one that will substantially balance the implement regardless of which portion thereof is being used; and to afford interchangeability.

The butt end of the ferrule preferably increases in diameter, or flares, to such an extent as will exceed the diameter, or size, of the eyelet and its collar. So shaped, the ferrule may be driven tightly into the eyelet from the under side of the member 10 and retained securely in an operable position by any means such as a bolt or pin (not shown) through the collar, 14, and handle. Or the ferrule may be secured by driving a wedge or

tapered plug 22 into the butt end thereof from the under side of the implement.

The eyelet is preferably oval shaped, and likewise the butt end of the ferrule, to prevent its twisting or turning out of position.

5 The upper portion of the handle 16a may be of wood or other material to reduce the weight of the instrument, to deaden the shock and vibrating reaction upon the user, and for other obvious 10 reasons. The wooden portion of the handle may be secured to the metallic ferrule portion 16 by 15 any suitable means such as a bolt or pin.

The ferrule eyelet is preferably, though not necessarily, located nearer one end of the elongated member than the other. Thus located the 15 blade portion 13a is afforded strength, a better balance, and, too, the greater portion of the implement, located between the eyelet 15 and end 20 12 acts as a driving weight when the blade 13a is employed as a grubbing hoe or trencher.

20 A further object of my invention is a particular shaped handle or combined handle and ferrule that will balance the implement whether it be used in a pulling position as a rake, 17, or as 25 a scraper, 18; whether it be used in a horizontally swinging scythe-like fashion; whether it be used in a pushing fashion as a spade when employing the end 12; whether it be used in a pulling fashion as a furrower or trencher when employing the 30 end 13; or whether it be used in a vertical stroking fashion when employing the blade 13a as a grubbing hoe, axe or the like.

35 To accomplish this balancing effect I provide a handle or combined handle and ferrule so shaped that a portion extends upwardly substantially perpendicular to the flat elongated member where it continues into a portion at an angle from the perpendicular portion in a direction toward the longer portion of the flat member and thence continues into a portion at an angle back 40 upon itself and toward the shorter portion of the flat member substantially as shown.

40 It is to be understood that I do not limit my

invention to the specific embodiments herein described. The structures defined herein are set forth for the purpose of illustrating practical embodiments of my invention and by which the invention may be practiced. It is to be further understood that no limitations are to be imposed upon my invention except such as are indicated in the appended claims.

5 From the foregoing it will be understood that I have provided a single sturdy implement that 10 will withstand heavy and rough usage; that will accomplish the purposes and functions of a number of various single implements; and an implement that may be easily and conveniently carried and handled. Its utility, adaptability, and availability for various required purposes being one of its most outstanding features of novelty.

15 I claim as my invention:

1. A tool comprising a substantially flat elongated member having a centrally disposed longitudinal raised reinforcing portion extending into an upright collar about an eyelet longitudinally-decentered with respect to said elongated member, said elongated member having a serrated tooth-like edge, a blade-like edge, a hoe-like end, 25 and a handle ferrule detachably engaging said elongated member within the eyelet thereof.

2. The combination of an elongated working member having an orifice longitudinally-decentered with respect to said elongated member, a 30 handle, and a tapered ferrule connecting the handle and wedge wise connecting the working member within said orifice, said handle and ferrule being adapted to afford a directional force by having a portion thereof extend upwardly 35 from the working member substantially perpendicular thereto and continuing into a portion at an angle to the perpendicular portion and in a direction toward the longer portion of the working member and thence continue at an angle back 40 upon itself and toward the shorter portion of the working member substantially as shown.

JOHN H. WEGNER.
